UNITED STATES PATENT OFFICE.

THEODORE A. EICHHORN, OF OAK PARK, ILLINOIS, ASSIGNOR TO VICTOR T. TOBOLLA,
OF CHICAGO, ILLINOIS.

BUNION PROTECTOR.

Application filed May 16, 1921. Serial No. 469,783.

To all whom it may concern:

Be it known that I, THEODORE A. EICHHORN, a citizen of the Republic of Germany, residing at Oak Park, in the county of Cook 5 and State of Illinois, have invented new and useful Improvements in Bunion Protectors, of which the following is a specification.

This invention relates in general to devices or appliances adapted to protect and 10 reduce the discomfort of foot deformities, and has more particular reference to an appliance adapted to serve as a protector for bunions or enlarged joints.

Various devices of rubber have heretofore 15 been employed for this purpose, which were adapted to be placed around or close to the bunion or joint, and directly against the foot inside the stocking. An appliance of this character, however, readily becomes dis- 20 placed and frequently becomes improperly positioned in the act of drawing on the sock or stocking. Furthermore, these appliances are imperforate, and therefore result in heating and discomfort of the foot, and as they 25 are made in a few sizes and thicknesses only, they do not properly fit many bunions which project to various degrees from the foot, and consequently an appliance which is of im- 30 proper size or thickness aggravates the pressure on the deformity and increases instead of diminishing the discomfort.

One of the primary purposes of my pres- 35 ent invention is to provide a protector which can be sewed to the stocking or sock upon the outside so that it will not become dis- placed when drawing on the stocking, and will be held by the stocking in proper po- 40 sition with respect to the protuberance on the foot.

Another object is to provide a protector 45 which is capable of adjustment to provide greater or less thickness on one side or the other of the bunion so that the user may adapt and adjust the device to the partic- 50 ular dimensions which give the greatest com- fort.

A further feature of my invention resides 55 in the fact that the protector is ventilated so that it does not cause heating or irritation of the foot, and furthermore, being outside the stocking and not in direct contact with the foot, it is very sanitary, and the construction is such that the rubber pads may be removed and the casing or pockets in which they are carried may be washed with

the stocking, thus adding to the sanitary character of the protector.

Other objects and many of the inherent advantages of my invention will be readily appreciated as the same becomes better un- 60 derstood, by reference to the following de- scription, when considered in connection with the accompanying drawings:

Referring to the drawings:

Fig. 1 is a side view of a foot showing 65 the application of my improved protector thereto;

Fig. 2 is an enlarged plan view of one of my protectors;

Figs. 3 and 4 are sectional views on the 70 lines 3—3 and 4—4 respectively of Fig. 2;

Fig. 5 is a detail of one of my improved pads;

Fig. 6 is a detail of the inner pad;

Fig. 7 is a transverse sectional view show- 75 ing three pads in assembled relation;

Fig. 8 is a plan view partially in section, of a modified form of my invention; and

Fig. 9 is a sectional view through the pro- 80 tector shown in Fig. 8.

In the construction of my improved pro- 85 tector, I employ first, a ply 11 of suitable textile fabric such as linen or cotton, for in- stance, which is shaped in outline to sub- stantially the form illustrated in Fig. 2, and is provided with a central aperture 12 adapt- 90 ed to surround a bunion or enlarged joint. Upon one face of this fabric ply, I impose two smaller flaps or fabric pieces 13 and 14 respectively, each of which has its edge spaced inwardly from the perimeter of the 95 ply 11, leaving a projecting margin 14 of this last-mentioned ply, as will be apparent from Figs. 2 and 4. These flaps 13 and 14 are securely stitched around their longitudi- 100 nal and curved margins by a row or rows of stitching 15 to form pockets closed at the sides and ends of the ply 11, but open at the center adjacent the aperture 12. It will be observed from Fig. 2 that the open ends 105 of these pockets are spaced apart so that access to the pockets may be had, and that the opposed edges of the plies 13 and 14 are recessed at 16 in substantial conformity to the contour of the underlying aperture 12. 105

The ply 11 with the plies 13 and 14 secured thereto as described, provide a carrier or container for the reception of pads, which serve to protect the swollen and projecting portion of the foot from being pressed 110

against or rubbed by the shoe. In each of these pockets, I therefore insert a tapered and properly shaped pad 17 of rubber or other yielding material, which is adapted to 5 take the pressure of the shoe and prevent it from rubbing against or irritating the projecting and tender deformed portion of the foot which lies within the aperture 12, and between the opposed ends of the pads 17 10 which are recessed to conform to the recesses 16 and the aperture 12. The rubber or other flexible and yielding pads 17 may be of various thicknesses, and these pads may be interchangeable so that one or both may be 15 removed and another of greater or less thickness be substituted therefor to suit the requirements of any particular deformity. 80

Preferably, however, my invention contemplates the employment of a composite 20 pad, consisting of a plurality of interlocking plies, any desired number of which may be assembled together to produce a pad of the desired thickness. Such a composite pad is illustrated in Fig. 7 wherein it will be observed 25 that the outer ply or layer 18 is shaped to fit the pocket in the container and is provided with a plurality of sockets or openings 19 adapted to receive lugs or studs 21 projecting from the outer face of a 30 second underlying pad layer 22. This layer is illustrated in Fig. 5, from which it will be observed that three of the studs 21 project from the outer face of the pad layer and are adapted to engage in the openings or 35 sockets 19 of the outer layer 18. The two layers, when assembled, provide a pad of increased thickness, and should it be desirable to further increase the thickness of the pad, a third or inner layer 23 is attached to the 40 under face of layer 22 by means of studs 24 projecting outwardly from layer 23 and engaged in sockets 25 formed in the layer 22. This scheme of interlocking layers to build 45 up a pad of the requisite thickness may be carried even further and four or even more pad layers may be thus assembled to provide a composite pad of requisite thickness for any foot. 105

In order to provide for ventilation, the 50 pads, whether solid or of built-up construction, are equipped with ventilating perforations 26 which permit of air circulation through the pads, thus adding to the sanitary qualities of the device and preventing 55 overheating of the foot and stoppage of the pores. 110

When the protector has been assembled with the pads either of integral or composite construction disposed in the respective 60 pockets, the protector may be placed on the foot, the stocking first having been drawn on into position, whereupon the protector is secured to the stocking by a row of stitches 27 passing through the margin 14 of the 65 ply 11 and through the underlying stock- 115

ing or sock. The protector is thus securely fastened to the stocking and is held thereby against accidental displacement, with the result that it is always maintained in the requisite relation with respect to the bunion 70 and protects it against injury and rubbing by the shoe. Upon removal of the stocking, the protector remains attached and may be drawn on again and will always assume its proper position. When the stocking is 75 washed, the pads are simply withdrawn from the pockets and the textile carrier remains attached to the stocking and is washed therewith so that it is always kept in sanitary condition. 80

In Figs. 8 and 9, I have shown a modified form of my invention, wherein the underlying ply 28 which is attached to the stocking, has secured to its upper face a ply 29 forming a circular pocket instead of two 85 elongated separate pockets, as previously described. The pad 31 in this instance is also of generally circular form and may be inserted through the openings 32 in the upper ply 29 by simply bending or doubling up 90 the pad so that it can be introduced into the position shown in Figs. 8 and 9. The pad in this instance may be of either integral or built-up construction, and is provided with the ventilating openings 33 similarly to the 95 pads previously described. This form of invention is more particularly adapted for small bunions such as develop on the outer side of the foot, although it may be used on the big toe joint if the bunion is not so 100 large as to require the form of the invention shown in Figs. 1 to 7 inclusive. In this instance also, the margin of the ply 28 is sewed to the stocking so that it is held in position and is washed with the stocking, 105 the pad being removed through the opening 32 and re-inserted when the stocking is again to be worn. 110

It will be apparent from the foregoing that I have provided a protector which is 110 adjustable, to provide pads of the required thickness which may be increased or diminished as desired; that the protector is attached to the outside of the stocking by which it is always held in proper position against displacement; that the protector is ventilated and sanitary; that it may be washed and kept in sanitary condition, and that the pads may be easily removed and replaced when necessary. 115 120

It is believed that my invention, its construction, mode of use and many of its attendant advantages will be understood from the foregoing without further description, and while I have shown and described preferred embodiments, obviously the form of the invention can be varied within considerable limits without departing from the essence of the invention as defined in the following claims. 125 130

I claim:

1. A bunion protector, comprising a holder formed of textile fabric and provided with a pocket opening toward the center thereof, and a tapered protective pad of yielding material removably disposed in said pocket.
2. A bunion protector, comprising a ply of textile fabric provided with an opening, a plurality of pockets attached to one face 10 of said ply with their open ends disposed toward said opening, and a protective pad of yielding material removably disposed in each of said pockets.
3. A bunion protector, comprising a holder 15 formed to fit over a bunion and provided with pad-receiving pockets opening toward the center of said holder and a protective pad removably disposed in each pocket, said pads each comprising a plurality of layers 20 of flexible material and means for detachably connecting said layers together.
4. A bunion protector, comprising a holder provided with pad-receiving pockets and pads removably disposed in said pockets,

each of said pads comprising a plurality of 25 layers of yieldable material provided with means for detachably interlocking said layers together.

5. A bunion protector comprising a holder provided with a pocket and a yielding pad 30 removably disposed therein, said pad comprising a plurality of layers of material provided with openings and studs adapted to engage therein whereby said layers are detachably connected together. 35

6. A bunion protector, comprising a holder having a pad receiving pocket, and a multi-ply pad disposed in said pocket, the plies thereof being provided with interengaging means whereby the plies are detachably interlocked. 40

7. A bunion protector, comprising a holder provided with a pad receiving pocket, and a pad disposed therein provided with ventilating openings, comprising a plurality of 45 plies having interengaging provisions whereby the plies are locked together.

THEODORE A. EICHHORN.
